UNITED STATES PATENT OFFICE

HARVEY H. RUMPEL, OF MILWAUKEE, WISCONSIN, ASSIGNOR TO SMITH ENGINEERING WORKS, OF MILWAUKEE, WISCONSIN, A CORPORATION OF WISCONSIN

CRUSHER MILL DRIVING MEANS

Application filed October 19, 1928, Serial No. 313,460. Renewed November 7, 1931.

This invention relates to improvements in crusher mill driving means.

It is one of the objects of the present invention to provide a crusher mill driving means in which the driving mechanism may be easily removed from the crusher without disturbing the crusher head shaft or sleeve, or the crusher head shaft and sleeve may be removed without disturbing the driving mechanism.

A further object of the invention is to provide a crusher mill driving means in which the driving means and the crusher head sleeve are journaled on conical rollers in a manner to permit the easy separation of some of the parts without disturbing others, which is of considerable importance in repair or replacement of parts.

A further object of the invention is to provide a crusher mill driving means having a means for forcibly oiling all of the bearings of the driving mechanism, and also the bearings of the crusher head shaft and sleeve.

A further object of the invention is to provide a crusher mill driving means which is of simple construction, is strong and durable, and is well adapted for the purpose described.

In the accompanying drawing in which the same reference characters indicate the same parts in all of the views:

Fig. 1 is a vertical sectional view of the lower portion of the improved mill; and

Fig. 2 is a horizontal sectional view thereof taken on line 2—2 of Fig. 1.

Referring to the drawing, the numeral 5 indicates a lower frame or casing which is of cylindrical form and is provided with an inner upwardly extending bearing 6 which terminates at its lower end a distance above

the lower portion of the casing. A vertical tubular sleeve 7 is journaled in the bearing 6 and is formed with a tapered obliquely extending eccentric bore 8. A tapered crusher head shaft 9 is journaled in the bore 8 of the

sleeve shaft, and the lower end of the sleeve shaft is supported on a conical roller bearing 10 which is interposed between said lower end portion of the sleeve shaft and the removable cap plate 11 forming part of the casing 5.

An annular shoulder 11' holds the bearing

in position. As constructed the downward strain of the crushing head is borne by the sleeve shaft and from said sleeve shaft to the frame, thus materially differing from crushers in which the strain is borne by the shaft of the head.

A bevel gear 12 loosely mounted on and keyed to the lower end portion of the sleeve shaft 7 is in mesh with and driven by a bevel pinion 13 which is mounted on the inner end of a horizontal driving shaft 14. Said driving shaft is journaled in conical roller bearings 15 and extends through the side extension frame or casing 16 and at its outer end is provided with a pulley 17 for connection with a source of drive, not shown.

The horizontal shaft 14 and its bearings 15 extend through and are supported in a supplemental frame or casing 18, of cylindrical form in cross section, which extends into the extension casing or frame 16 and at its inner end portion has an annular and shouldered connection 19 therewith. A medial portion of the supplemental casing is formed with an annular longitudinal flange 20 which snugly fits into the extension portions of the casing 5 to prevent lateral movement of the supplemental casing. Said supplemental casing is also provided with a radial flange 21 which is spaced a slight distance from the end of the casing extension 16 and is formed with openings for receiving bolts 22 to firmly clamp the shoulder 19 against the side of the casing 5 and hold the supplemental casing firmly but easily removably in position.

The horizontal shaft 14 also has a geared connection 23 with an oil pump 24 for forcing oil to various portions of the mill. A pump 24 connected to an oil tank 25 draws the oil therefrom and forces it into the eccentric bore of the vertical sleeve by means of the pipe 26. The sleeve shaft 7 is formed with a duct 27 to permit the passage of the oil to the upper portions of the mill. The crusher shaft, the lower bearing, the gears and bearings of the drive shaft are also lubricated from the same source. The sleeve shaft 7 is also provided with an outer duct 28 for lubricating the bearing of the sleeve.

A pipe 29 extending upwardly from the gearing chamber 30 is provided for permitting the return of the oil from upper portions of the mill. From said chamber the oil flows 5 through the cap duct 31 to the return pipe 32 and to the oil tank 25, thus providing for a constant circulation of oil through the mill.

A duct 33 permits the oil to flow from the gear chamber 30 to the shaft and gear chamber 34 to lubricate the bearings of the shaft 14, and a return pipe 35 connected to the chamber 34 and the oil tank returns the oil from said chamber to the oil tank.

A tubular casing part 36 connects the pump 15 to the supplemental casing 18 by bolts 36' so that when desired the tubular casing may be easily removed to separate the pump gears 23 from each other.

The pump shaft 37 is formed in two parts 20 connected together by a keyed collar 38 which permits the easy separation of the shaft parts.

Particular attention is directed to the fact that the driving portion of the mill forms a 25 unitary structure or is self-contained with the casing so that in use it is not necessary to provide a separate bearing for the outer end portion of the horizontal shaft as in the ordinary mill. This construction also permits 30 the use of a shorter horizontal or counter shaft.

From the foregoing description it will be seen that the crusher mill driving means is of 35 very simple construction and provides a direct and positive drive and a force feed lubricating means for oiling all of the bearing parts. It will further be seen that the construction permits the separation and removal of parts with the minimum amount of labor.

40 What I claim as my invention is:

1. In combination, a main frame having bottom and side openings with vertical and horizontal bores disposed concentrically of said openings respectively, a removable closure cap for said bottom opening spaced from the lower end of said vertical bore, an eccentric rotatable in said vertical bore and having annular thrust bearing engagement with said cap, a gear secured to said eccentric in the space between said cap and the lower end of said vertical bore, said gear and annular bearing being axially removable through said lower opening upon removal of said cap, a tubular casing provided with horizontally 50 spaced guide bearings and having an end extending into said horizontal bore through said side opening, a drive shaft supported in said guide bearings, a pinion secured to the end of said drive shaft within said main frame and meshing with said gear, means for applying power to the opposite end of said shaft beyond said bearings, a pump operable from the portion of said shaft between said bearings, means for conducting lubricant 55 from said pump to the interior of said thrust

bearing and eccentric through said cap, and means for returning lubricant to said pump from the exterior of said eccentric and thrust bearing through said cap.

2. In combination, a main frame having bottom and side openings with vertical and horizontal bores disposed concentrically of said openings respectively, a removable closure cap for said bottom opening spaced from the lower end of said vertical bore, an eccentric rotatable in said vertical bore and having annular thrust bearing engagement with said cap, a gear secured to said eccentric in the space between said cap and the lower end of said vertical bore, said gear and annular bearing being axially removable through said lower opening upon removal of said cap, a tubular casing provided with horizontally spaced guide bearings and having an end extending into said horizontal bore through said side opening, a drive shaft supported in said guide bearings, a pinion secured to the end of said drive shaft within said main frame and meshing with said gear, means for applying power to the opposite end of said shaft beyond said bearings, a pump operable from the portion of said shaft between said bearings, means for conducting lubricant from said pump to said guide bearings in succession and from one of said bearings to said pinion, means for conducting lubricant from said pump to the interior of said thrust bearing and eccentric through said cap, and means for returning lubricant to said pump from the exterior of said eccentric and thrust bearing and from said pinion and gear through said cap.

3. In combination, a main frame having bottom and side openings and a vertical bore disposed in line with said bottom opening, a removable closure cap for said bottom opening, an eccentric rotatable in said vertical bore, an annular thrust bearing between the lower end of said eccentric and said cap, said thrust bearing being axially removable through said lower opening upon removal of said cap, a tubular casing forming a closure for said side opening and having horizontally spaced guide bearings, a drive shaft supported in said guide bearings, gearing interposed between said eccentric and the end of said shaft nearest said frame, means for applying power to the opposite end of said shaft beyond said guide bearings, a pump operable from the portion of said shaft between said guide bearings, means for conducting lubricant from said pump to said guide bearings in succession and from one of said guide bearings to said gearing, means for conducting lubricant from said pump to the interior of said thrust bearing and eccentric through said cap, and means for returning the lubricant to said pump from said gearing.

4. In combination, a main frame having

bottom and side openings and a vertical bore disposed in line with said bottom opening, a removable closure cap for said bottom opening, an eccentric rotatable in said vertical bore, an annular thrust bearing between the lower end of said eccentric and said cap, said thrust bearing being axially removable through said lower opening upon removal of said cap, a tubular casing forming a closure 5 for said side opening and having horizontally spaced guide bearings, a drive shaft supported in said guide bearings, gearing interposed between said eccentric and the end of said shaft nearest said frame, means for 10 applying power to the opposite end of said shaft beyond said guide bearings, a pump operable from the portion of said shaft between said guide bearings, means for conducting lubricant from said pump to the interior of 15 said thrust bearing and eccentric through said cap, and means for returning the lubricant to said pump from said gearing.

5. In combination, a main frame having bottom and side openings with vertical and horizontal bores disposed concentrically of 20 said openings respectively, a removable closure cap for said bottom opening spaced from the lower end of said vertical bore, an eccentric rotatable in said vertical bore and having 25 annular thrust bearing engagement with said cap, a gear secured to said eccentric, said annular bearing being axially removable through said lower opening upon removal of 30 said cap, a tubular casing provided with horizontally spaced guide bearings and having 35 an end extending into said horizontal bore through said side opening, a drive shaft supported in said guide bearings, a pinion secured to the end of said drive shaft within 40 said main frame and meshing with said gear, means for applying power to the opposite end of said shaft beyond said bearings, a pump operable from the portion of said shaft 45 between said bearings, means for conducting lubricant from said pump to the interior of said thrust bearing and eccentric through said cap, and means for returning lubricant to said pump from said gear.

50 In testimony whereof, I affix my signature.
HARVEY H. RUMPEL.
